Primary Examiner — Michael A Maharajh(74) *Attorney, Agent, or Firm* — Epstein Drangel LLP; Robert L. Epstein(57) **CLAIM**

The ornamental design for a vibratory massage device, substantially as shown and described.

DESCRIPTION

FIG. 1 is a front elevation view of the vibratory massage device of the present invention;

FIG. 2 is a back elevation view thereof;

FIG. 3 is an elevation view of the left side thereof;

FIG. 4 is an elevation view of the right side thereof;

FIG. 5 is a top plan view thereof;

FIG. 6 is a bottom plan view thereof;

FIG. 7 is a perspective view showing the bottom and right side thereof; and,

FIG. 8 is a perspective view showing the top and left side thereof.

The broken lines shown in the figures are for the purpose of illustrating portions of the vibratory massage device, which form no part of the claimer design.
